CLAIM

The ornamental design for an earphones case, as shown and described.

DESCRIPTION

FIG. 1 is a first perspective view of an earphones case, according to a first embodiment;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a first perspective view of an earphones case, according to a second embodiment;

FIG. 10 is a second perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

The dashed broken lines in the figures show features of the earphones case that form no part of the claimed design.

The dot-dash broken lines illustrate bounds of claimed surfaces in the claimed design.
